METHOD OF FORMING CONTAINERS

Henry K. Powell, Chicago, Ill., assignor, by mesne assignments, to President and Directors of the Manhattan Company, New York, N. Y., a corporation of New York, trustees for Gibson Patent Containers, Ltd., New South Wales, Australia, a corporation

Application June 17, 1936, Serial No. 85,720

1. Claim. (CL 229—5.7)

The present invention relates to containers of the type having a flexible fibrous body portion constructed of a material such as paper board or the like, and has particular reference to an improved top construction in which a metallic rim portion is secured to the container when the latter is set up or erected.

A principal object of the invention is the provision of a flexible fibrous container having an improved metallic rim portion secured about its upper edge.

An additional object is the provision of a container having a flexible fibrous body portion provided with a strip secured adjacent its upper edge and an improved metallic rim member loosely fitted over the upper edge of the body portion and the strip in such a manner that one portion of the rim member fits beneath the strip to prevent vertical displacement of the rim and a channel portion of the rim member secures the body portion of the container against inward flexing.

A still further object is the provision of an improved method of producing containers of the type described and a means for erecting the same from collapsed condition, the improved container being rigid and particularly adapted for purposes such as the packaging of ice cream or the like.

These and other objects will be observed from a consideration of the following specification and by reference to the accompanying drawing, in which

Fig. 1 is a side view, partly broken away, of a container and rim member constructed in accordance with the invention;

Fig. 2 is a sectional view taken through the center of the container and showing an initial stage in the mounting of the rim member on the body portion of the container;

Fig. 3 is a fragmentary view similar to Fig. 2 and shows a second stage in the mounting of the rim on the container; and

Fig. 4 is a view similar to Fig. 3 showing a final stage in the mounting of the improved member on the container body portion.

Within recent years the practice of packaging ice cream in fibrous containers has been recognized as being highly desirable from many standpoints, such as economy, convenience and sanitation. Generally, the containers are constructed of flexible fibrous body members produced from paper board. To provide added strength for the bottom and top edges of containers of this type, it has been suggested to

employ metallic rim portions of various types, although such rim portions have been satisfactory from many standpoints. Several structural limitations to these rim members and their mode of attachment have made their use objectionable. In accordance with the present invention these objections very largely are eliminated and there is provided a container and rim member which are easily assembled and when so assembled provide a construction of great utility.

In the embodiment of the invention shown in the drawing the container 10 composed of a fibrous flexible body portion of tubular construction is provided with vertically extending score lines 11 dividing the body portion into a series of adjacent vertical strips. This type of container is of well known construction and when a commodity such as ice cream is frozen in the container the commodity expands, with the result that the score lines 11 assist in maintaining a uniform finished package.

Adjacent the upper edge 12 of the body portion of the container is provided an outer strip 13. This strip may be produced by turning the upper portion of the body member over prior to securing the body portion in tubular form. However, separate strips may be provided for this purpose. The strip 13 preferably is glued to the body portion of the container along its outer surface so that the strip will be rigidly attached in its proper position. It will be noted that the strip has an upper edge 14 which is on the same level as the upper edge 12 of the container and that the lower edge 15 of the strip forms an outwardly extending flange along a line spaced below the top edge of the container.

The rim member which is employed in connection with the container described is indicated generally at 16 and preferably is constructed of a metal such as aluminum. The rim member 16 has a vertical wall portion 17 of annular construction. The lower end of this wall terminates in an inwardly extending flange or lip portion 18. Adjacent its upper end the rim member is turned inwardly and downwardly to provide a channel member 19.

As may be seen in Fig. 2 the inside diameter of the annular wall 17 is substantially the same as the outside diameter of the strip 13, while the lip portion 18 extends inwardly to form an annular flange of less diameter than the outside diameter of the strip 13. The wall 17 is of substantially the same height as the vertical strip 13, and the channel member 19 is spaced from this wall a distance sufficient to receive the strip

13 and the body portion of the container. This rim member is mounted over the strip member 13 and the upper edge of the body portion of the container in such a manner that the flange 18 is positioned beneath the strip 15, thereby preventing upward retraction of the rim member from its position on the container, and the channel member 19 extends over the tops of the strip member 13 and the upper edge 12 of the 5 container and downwardly a short distance along the interior wall of the body portion of the container. The rim member is loosely fitted in the manner described. That is, the rim member is preformed and the body portion of the 10 container and rim member are assembled by the user when it is desired to set up the container. This assembling does not include crimping or forming the metal in such a manner as to make it pinch or clamp the material of the body 15 portion.

In mounting the rim member about the container, the upper edge of the body portion of the container is flexed inwardly a distance sufficient for the strip 13 to pass within the flange 18. 20 The container then is moved vertically with respect to the rim member and the upper edge of the container again is flexed outwardly after it is past the inner edge of flange 18. Upon the continued vertical movement of the body portion 25 with respect to the rim member the upward edge of the body portion passes into and is received by the channel 19 of the rim member. Upon still further movement of the container with respect to the rim member, the flange 18 passes below the lower edge 15 of the strip 13 30 and the upper edge of the container and the strip 13 snap outwardly to assume the position shown in Fig. 4.

To assist in assembling the rim and body member there preferably is provided an annular funnel-shaped flange 20 having its narrow edge of the diameter substantially the same as the inside diameter of the lip member 18. The member 20 flares outwardly from this position so 40 that the body portion of the container and the strip 13 easily may be received therewithin. As the container is pressed upwardly into the member 20 the strip 13 contacts the inclined funnel-shaped walls thereof and the upper portion of the container is flexed inwardly a sufficient distance for the strip 13 to pass within the flange 18. In Fig. 2 the movement has progressed so 45 that about one-half of the strip 13 is within the flange member 18. A second and reversely flared flange 21 has an upper edge of substantially the same diameter as the inside diameter of the channel member 19 and is flared inwardly and downwardly therefrom. As the upper edge 50 of the container passes within flange 18 it strikes the inclined walls of the member 21 and is deflected outwardly. The upper edge of the member 20 is fitted adjacent the flange 18 and the upper edge of the member is fitted adjacent the lower edge of the channel member 19, as shown 55 in Fig. 2. It will be understood that these members are carried on suitable frame structures not shown and that the rim member 21 will be held in the position shown in Fig. 2 until the strip 13 has been received within the rim member. Any 60 suitable means for withdrawing the container

from members 20 and 21 after the rim is mounted thereto may be employed. As shown in Fig. 4, the engagement of the rim member with the upper edge of the body portion of the container and the strip 13 is complete and the container is being removed from the assembly elements 20 and 21 by continuing the movement of the container upwardly, it being understood that in this method the rim member is mounted in the manner described prior to provision of a bottom. 10

The construction of the container includes the formation of a flexible fibrous body portion in any suitable manner and the provision of a double edge about the upper edge of the container. In the embodiment of the invention 15 shown in the drawing, the rim member is mounted thereabout as described and thereafter any suitable bottom construction may be provided. The metallic rim member is permanently attached to the body portion, particularly after 20 the container is filled with a commodity which prevents the inward flexing of the body portion below the lower edge 15 of strip 13. The strip 13 provides an outwardly extending ridge which has sufficient body to prevent removal of the 25 metallic rim, and may be somewhat different from the particular construction shown in the drawing. The engagement of flange 18 beneath the lower edge 15 prevents movement of the strip vertically with respect to the container. 30 Channel member 19 extends downwardly a distance sufficient to prevent the body portion from being flexed inwardly. In this manner the flange 18 is maintained in engagement beneath the edge 15. After assembling the rim member 35 16 to the upper edge of the container, the container may be employed in the usual manner and after filling with ice cream or some other commodity a conventional cover 22 may be placed over the top of the container in the usual 40 manner.

Many changes may be made in the structure described herein for purposes of illustration and explanation without departing from the scope of the invention and such changes are intended to 45 be included in the appended claim.

I claim:

The method of forming a container, which comprises forming a body portion of flexible fibrous material, providing a paperboard strip 50 adjacent the upper edge of the body portion, forming a metallic rim member having an inwardly extending lip portion along its lower edge of smaller diameter than the diameter outside of said strip and having an upper channel member formed by an inwardly and downwardly turned lip portion for receiving said strip and the upper edge of said body portion, flexing said upper edge inwardly and moving the same past the lower lip portion of said rim member, expanding said upper edge sufficiently to enter said channel portion upon further movement and before the lower edge of said strip passes said lower lip, and moving said body portion further with respect to said rim to cause said lower lip to 60 pass beneath the lower edge of said strip while the upper edges of said body portion and strip are within said channel member. 65
